UNITED STATES PATENT OFFICE.

FREDERICK R. KALDENBERG, OF NEW YORK, N. Y.

DESIGN FOR A CANE-HANDLE.

SPECIFICATION forming part of Design No. 18,782, dated December 4, 1888.

Application filed November 8, 1888. Serial No. 290,332. Term of patent 7 years.

To all whom it may concern:

Be it known that I, FREDERICK R. KALDENBERG, a citizen of the United States, residing at New York, in the county and State of New York, have invented and produced a new and original Design for Cane-Handles, of which the following is a clear and exact specification, reference being had to the accompanying drawing, forming a part thereof, and 10 which is a side elevation of a cane-handle, showing my new design.

The leading features of my design consist in the peculiar configuration of the handle and the raised floral and beaded ornamentation.

15 *a* is the handle, which has an irregular outline and tapers to the outer end. *b* is a raised line crossing the same about midway of its length, and terminating at each end thereof in 20 a scroll or volute, *c c'*, forming an S-shaped figure. Within and following this outline is a ribbed line, *e*. Within the larger scroll, *c*,

is a polygonal figure, *f*, of short raised lines radiating from a central embossment, *g*.

On the upper part of the handle is a leaf-like figure, *h*, having below it a scalloped outline, *i*, surrounding a ribbed surface, *j*.

25 *l l* are raised figures of a fan shape spreading out at the top, and between these figures is a small volute, *m*, formed of a plain and 30 a beaded line and having a central embossment, *n*.

Midway of the S-shaped figure springs a beaded line, *o*, which forms the contour-line 35 on the lower edge of the tapered end of the handle, which line is lost in the volute *c'*.

What I claim as new, and desire to secure by Letters Patent, is—

The design for cane-handles herein shown and described.

FREDERICK R. KALDENBERG.
